KEITH CLARK, OF RIDGEWOOD, NEW JERSEY

PAD CALENDAR

Application filed March 24, 1928. Serial No. 264,561.

My invention relates more particularly to pad calendars although it is not necessarily limited to this particular type of product. Pad calendars usually consist of a number 5 of sheets of paper stacked upon each other, marked with the day, month and year, there being one sheet for each day of the year arranged in chronological order to serve as a calendar, with space on each sheet for writing. The sheets are usually clamped to a base or platen which is held in an inclined position and the sheets are adapted to be torn off from day to day, so that the current date will be displayed on the topmost sheet. 10 In the present device I provide means, such as a tearing plate, against which the sheets may be torn as they are removed from the stack, but I also provide for loosening the pressure upon the stack so that sheets may 15 be entirely removed from the device, if desired. When the sheets are severed against the tearing plate the stubs of the sheets are retained and when many sheets have been torn off these stubs prevent the co-operation 20 of the tearing plate, so that the sheets do not tear smoothly. It is desirable, at least after many sheets have been torn from the pad, to remove the entire sheet, including the stubs, and to have the means for holding the 25 stack follow down to accord with the decreased height of the stack, and I provide an arrangement for this purpose in the present invention. While supporting legs for holding 30 one end of the base or platen elevated above the desk or table are old, I have provided a combination which not only permits the use of the features above mentioned, but permits the legs to be detached for shipping 35 purposes and to be readily assembled for use. These legs and the parts associated with them 40 permit the calendar to remain in assembled condition during shipment notwithstanding the detachment of the legs.

45 In the drawing forming part of this application,

Figure 1 is a plan view of a pad calendar embodying my invention,

Figure 2 is a side elevation thereof fully 50 assembled;

Figure 3 is a sectional view taken on the line 3—3 of Figure 1,

Figure 4 is a view similar to Figure 3, showing the pad holding means or screws slackened off to permit the complete removal of 55 the sheets, and

Figure 5 shows details of various parts.

The pad calendar comprises principally the base or platen 1 adapted to be supported in an inclined position in relation to the table top, desk or other means 2 on which the calendar is placed; and in addition there is a stack of sheets 3 of paper mounted upon and supported by the base or platen 1. It will be understood that these sheets may be 60 simply blanks in which case the device will serve as a writing tablet, or they may be printed with consecutive dates representing the days of the year with the major portion of the sheet left blank for writing mem- 65 oranda. 70

There is a tearing plate 4 extending across the upper, fixed end of the stack of sheets and the front edge 5 of this plate is adapted to serve as a tearing edge for the sheets when 75 the latter are individually moved upwardly and drawn against the edge for tearing. It is common to use tearing plates for this purpose and I do not claim the same, per se, as my invention. There are shown two screws 80 6 which extend through apertures in the tearing plate 4 the screws having heads 7 adapted to engage the top surface of the tearing plate and these screws may be manipulated by gripping the heads with the 85 fingers or with a screw driver or other instrument. The shanks of the screws pass through apertures in all of the sheets of the stack and the lower ends of these screws are 90 screwed into a nut or attaching member 95 which is secured to the base or platen 1.

The nut or attaching device which is attached to the base 1 is composed of two sections threaded one into the other. The one 95 which is shown as the upper section 8 in the drawing comprises a flat head 9 which is adapted to press against the upper surface of the base 1; and this member has a tubular portion 10 provided with an internally threaded bore 11 into which the shank of the screw 100

engages. In addition it has an exterior thread 12 which is adapted to screw into the internal thread 13 of the second member 14. The second attaching member 14 also has a flat head 15 which is adapted to engage the under surface of the base 1. This member also has a tubular portion 16 which extends into an aperture 17 in the base 1. The sections of the attaching member are assembled 5 from the top and bottom of the base, the tubular portions 10, 16 being inserted in a suitable aperture 17 in the base and the external thread 12 of the member 8 is screwed into the internal thread 13 of the member 14 until 10 the heads 9, 15 of the members are clamped tightly against the upper and lower surfaces 15 of the base member 1. These attaching members remain in this condition during shipment and as long as the device is in use. It 20 will be noted that the tubular extension 10 of the member 8 projects only partly through the internally threaded aperture of the member 14.

The leg member 19 is shown as a hollow 25 tube with a closed bottom end, the bore 20 serving to allow the clamping screw 6 to move downwardly therein. There is a reduced end 21 on the leg provided with an external thread 22 which is adapted to be 30 screwed into the internal thread 13 of the member 14 until the shoulder 23 of the leg tightly engages the head 15.

When the device is to be packed for shipment, the leg members 19 are detached by unscrewing them from the members 14 so that 35 the device may be packed in flat condition. The base, the stack of sheets, and the tearing plate, however, remain completely assembled because the attaching members 8, 14 tightly 40 grip the base member 1 and the screws 6 are held by these members and the screws in turn hold the stack and tearing plate in assembled condition. It may be stated that the screw attaching members and legs at opposite sides 45 of the calendar are duplicates of each other. When the calendar is to be set up for use the threaded portions 21 of the legs are screwed part way into the threads 13 of the member 14 and the legs then serve to support the 50 calendar in the position shown in Figure 2. If the holding screws 6 are screwed down tight they press the tearing plate 4 tightly upon the stack 3 and while this condition exists the sheets can be removed only by tearing 55 them against the front edge 5 of the tearing plate. As the stubs of the sheets, that is, the portions covered by the tearing plate, remain on the stack as the sheets are torn in this manner, it is difficult to tear the sheets neatly after 60 a number of sheets have been torn off, and the stubs left under the tearing plate, and the device becomes unsightly and clumsy looking. With the present device, however, the screws 6 may be slackened off slightly as shown in Figure 4, without disturbing the assembly of 65

the parts, and it is then possible to remove the sheets by pulling them endwise, so that they tear away from the shanks of the screws. In this case the entire sheet may be removed, so that no stub is left. The screws 6 may or 70 may not be turned down snug again onto the tearing plate after the sheet has been removed. However, after many sheets have been removed from the stack, it is desirable to turn down the screws 6 so that the heads 7 will 75 follow the tearing plate, in which case the shanks of the screws will extend below the attaching means and project into the bore 20 of the respective legs. The screws may be turned down to accord with the decrease 80 in the thickness of the stack, until substantially all of the sheets have been removed. When the stack of sheets has been consumed, the screws 6 may be removed, and likewise 85 the tearing plate 4 and a new stack of perforated sheets may be placed on the base and the screws 6 and the tearing plate may then be applied to the new stack. From the above it will be apparent that the attaching means may be assembled to remain a permanent part 90 of the base; that the screws 6 permit the plate 4 to be used as a tearing plate if desired, or they permit the pressure from the stack to be released, so that the sheets may be completely 95 torn away endwise and leave no stubs. The parts so far as the attaching members, stack 100 of sheets and tearing plate are concerned, may all be shipped in assembled condition, whereas the legs may be detached without disassembling or disarranging the remaining parts, and may be readily applied when the device is set up for use.

Having described my invention, what I claim is:

1. A device of the class described including a stack of sheets having perforations, a base therefor, a clamping device secured through and to said base and comprising members having heads for engaging opposite surfaces of said base and also tubular portions extending into said base, said tubular portions of said clamping members having, one an internal and the other an external thread to permit said members to be screwed together, one of said clamping members also having a threaded bore, and a threaded member passing through the perforations of the sheets and engaging in said threaded bore. 110

2. A device of the class described comprising a stack of perforated sheets, a base therefor, a clamping device for said base comprising co-operating members having portions for engaging against opposite faces of said base, one of said clamping members having a tubular portion provided with an external thread, and a threaded bore, the other clamping member having a tubular portion having an internal thread into which said external threaded tubular portion of said first member is adapted to screw, a de- 120

tachable leg for supporting a portion of said base and having a threaded portion also screwing into said internal thread of said second mentioned clamping member, and a 5 threaded member passing through said stack of sheets and screwing into said threaded bore.

3. A device of the class described comprising a stack of perforated sheets, a base 10 therefor, a clamping device for said base comprising co-operating members having portions for engaging against opposite faces of said base, one of said clamping members having a tubular portion provided with an 15 external thread, and a threaded bore, the other clamping member having a tubular portion having an internal thread into which said externally threaded tubular portion of said first member is adapted to screw, a de- 20 tachable leg for supporting a portion of said base and having a threaded portion also screwing into said internal thread of said second mentioned clamping member, and a threaded member passing through said stack 25 of sheets and screwing into said threaded bore, said leg having a bore to receive a portion of said member which passes through said stack.

Signed at the city, county and State of
30 New York, the 9th day of March, 1928.

KEITH CLARK.
